UNITED STATES PATENT OFFICE.

EDWARD J. BAILEY, JR., OF PHILADELPHIA, PENNSYLVANIA.

METALLIC BUILDING STRUCTURE.

Application filed November 30, 1923. Serial No. 677,847.

To all whom it may concern:

Be it known that I, EDWARD J. BAILEY, Jr., a citizen of the United States, residing at #1327 E. Montgomery Avenue, Philadelphia, State of Pennsylvania, have invented certain new and useful Improvements in Metallic Building Structures, whereof the following is a specification, reference being had to the accompanying drawings.

10 My invention relates to buildings constructed of sheet metal and ordinarily used as garages or out houses of various kinds.

Buildings of this type usually comprise a groundwork of structural iron which serves 15 as a skeleton frame for attachment of interchangeable closure, or wall panel sections; and the object of my invention is to embody structural features in such buildings that will facilitate their erection, insure 20 weather-tightness at the joints of the various constituent parts, and promote the rigidity of the parts in assemblage.

In the drawings, Fig. I is a plan sectional view, more or less diagrammatically represented, of a building structure conveniently illustrating the novel features of my invention.

Fig. II is a detail view on an enlarged scale showing the manner in which the ends 30 of the sheet metal wall panels are overlapped and attached to the skeleton frame of the building structure.

Fig. III is a detail view showing the manner in which corner joints are made between the panels of adjacent walls; and

Fig. IV is also a similar view showing in detail the construction of the front wall of the building.

Referring first more particularly to Fig. 40 I, it will be observed that the structure comprises a skeleton frame work comprehensively designated by the numeral 1, which consists of a multiplicity of uprights 2 preferably of angle iron, which, except at the 45 front wall, are equally spaced, and a number of connecting horizontals 3 also preferably of angle iron, with one of their flanges cut away at opposite ends for convenience of attachment by bolts 4 or their 50 equivalents to said uprights. To this skeleton frame 1 are hung enclosing side wall panels 5 which are preferably made of standard dimensions so as to be interchangeable with one another. With reference now 55 also to Fig. II, which shows a detail at "A" in Fig. I, it will be noted that at opposite

ends, the panels 5 have corrugations 6 with extended marginal flanges 7, said corrugations being spaced to correspond to the distance between the uprights 2 of the 60 frame 1.

As a result of this provision, the panels 5 may be so placed during assembling that their end corrugations 6 are brought into coincidence and to overlap centrally of the uprights 2 of the structural frame 1 as shown in the illustration last referred to. The marginal flanges 7 are thereupon secured against the portions of the respective panels lapped by them and to the horizontals 3 of the frame at opposite sides of the corrugations. For the latter purpose, fastening devices such as headed screws 8 that are provided at their inner ends with nuts 9 may be conveniently employed. Overlapping of 75 the end corrugations 6 of the panels 5 and securing of the flanges 7 at opposite sides of the verticals 2 as just explained, not only enhances the rigidity of the structure as a whole, but at the same time insures weather-tight junctures between contiguous panel sections 5, 5.

If desired, the panels 5 may be provided with additional corrugations 6^a intermediate those already described, such construction 85 rendering them more rigid against bending and also adding to their appearance. In order to facilitate assembling at the place of erection, the panels 5 are fabricated as complete units with the horizontals 3 of the 90 frame 1 permanently attached by bolts or rivets. Exception is however made at the ends so that the corrugations 6 can be subsequently overlapped and their marginal flanges 7 secured to the frame horizontals 3 95 as already explained.

Referring now to Fig. III which shows the construction of a corner joint at B in Fig. I, 10 indicates the rear end wall panel of the building. The contiguous side wall panel 5, has its end turned laterally to provide an out-standing marginal flange 11 adapted to be overlapped by marginal retroversion 12 of the panel 10. It is obvious that the relation of the inter-engaging means 100 of the two panels at their juncture may be reversed if desired, the construction in either case affording a rigid serviceable and weather-tight connection at the building 105 corners.

Referring again to Fig. I, attention will 110 now be directed to the front wall of the

building, said wall having at opposite sides of a central opening 15, columns or pillars each comprising a pair of the frame uprights 2. In this instance, the uprights involved are spaced closer than the uprights of the side walls and joined by comparatively shorter horizontals 3^a of angle iron. These details are brought out more clearly in Fig. IV showing the column indicated at 10 C in Fig. I on a much larger scale. Each of the columns is completed by a facing panel 16 embellished by a single central longitudinal corrugation 17. The outer end of the panel 16 may be formed with a retroverted margin 18 such as aforescribed in connection with the panel 10 to overlap a marginal flange 11 of the end panel section 5 of the adjacent side wall. The inner edges of the panel 16 are bent to L formation as at 15 19 thereby providing a jamb for the doors indicated at 20, which are hung upon hinges 21 secured by bolts 22 to one of the uprights 2 of the front wall. In addition to concealing the said uprights, the panels 16 serve in 20 an ornamental capacity in gracing the appearance of the front wall of the structure. 25

Having thus described my invention, I claim:

1. A metallic building structure including 30 in combination a skeleton frame of angle section uprights and connecting horizontals, the latter having one of their flanges cut away at opposite ends for convenience of attachment to the uprights, wall panels of sheet 35 metal adapted to be hung to the frame, said panels having their opposite ends corrugated with extended marginal flanges, said corrugations adapted for overlapping corresponding end corrugations of contiguous 40 panels, and means for securing the marginal flanges of the corrugations to the portions of the respective panels lapped by them and to the skeleton frame.

2. A metallic building structure including 45 a structural skeleton frame comprising a multiplicity of angle section uprights and connecting horizontals, the latter having one

of their flanges cut away at opposite ends for convenience of attachment to the uprights; in combination with wall panels of 50 sheet metal provided at opposite ends with corrugations, said panels adapted to be hung to the skeleton frame with the end corrugations of the contiguous units overlapping centrally of the uprights of said 55 frame.

3. A metallic building structure including a structural skeleton frame comprising a multiplicity of angle section uprights, and horizontals of like section having one of their flanges cut away at opposite ends for convenience of attachment to connecting the uprights; in combination with wall panels of sheet metal, having at their opposite ends, corrugations with extended marginal flanges, 60 said panels adapted to be hung to the skeleton frame with the end corrugations of contiguous units overlapping centrally of the uprights, and means for securing said marginal flanges to the portions of the respective panels lapped by them, and to the horizontals of the skeleton frame at opposite sides of the verticals. 65

4. A metallic building structure as claimed in claim 1 including exterior wall panels meeting at corner angles, one of said panels provided with an outwardly-turned lateral edge flange, and the other with a marginal retroversion adapted to embrace the edge flange of the first mentioned panel. 70

5. A metallic building structure as claimed in claim 1 including a front wall having at each side of a door opening, a pillar or column comprising a pair of spaced uprights of angle section, and a facing panel concealing the uprights, said panel having a single central longitudinal corrugation with the outer longitudinal edge retroverted and the inner parallel edge bent to L-formation to constitute a door jamb. 75

In testimony whereof, I have hereunto signed my name this 27th day of November, 1923, at Philadelphia, Pennsylvania.

EDWARD J. BAILEY, JR.
